UNITED STATES PATENT OFFICE.

JARVIS CASE, OF SPRINGFIELD, OHIO.

IMPROVEMENT IN GRAIN AND GRASS HARVESTERS.

Specification forming part of Letters Patent No. 12,714, dated April 17, 1855.

To all whom it may concern:

Be it known that I, JARVIS CASE, of Springfield, in the county of Clarke and State of Ohio, have invented a new and Improved Method of Constructing an Adjustable Mowing and Reaping Machine; and I do hereby declare that the following is a full, clear, and exact description of the same, reference being had to the accompanying drawings, and to the letters of reference marked thereon, making a part of this specification, in which—

Figure 1 is a plan view. Fig. 2 is a vertical section taken in the line xx , Fig. 1. Fig. 3 is an end view. Fig. 4 is a detached plan view of the adjustable head-iron and the other arrangements, which are subject to the same adjustability, with the exception of the bevel-pinion, which is stationary, the axle sliding through it when the head-iron, &c., are being adjusted. Fig. 5 is a back view of the same.

The nature of my invention consists in a new and improved method of constructing an adjustable mowing and reaping machine which is capable of being adjusted to a high or low cut with very little inconvenience and without changing the relative position of any part of the gearing, and also in placing the line-shaft above the center of the spur-gear of the driving-wheel for the purpose of admitting an adjustable anti-friction wheel with a spring-bearing of sufficient size to produce the desired result, and also to enable me to adjust my machine to a high or low cut, which could not be accomplished were the line-shaft placed in any other position.

To enable others skilled in the art to make and use my invention, I will proceed to describe its construction and operation.

A is the driving-wheel, which has its bearings at aa , as seen in Fig. 2. Said driving-wheel is provided with an internal spur-gear, as seen in Figs. 2 and 3.

B is the line-shaft, which has its bearings at bb . Said shaft is provided with a pinion, e , which takes into the gearing of the driving-wheel directly above the perpendicular center. This shaft extends entirely across the machine. The object of placing said shaft exactly above the perpendicular center of the spur-gear of the driving-wheel is—

First. To enable me to construct my machine in such a manner as to produce a perfect balance of all its parts. This I consider a very

desirable object to obtain, as machines of this kind cannot work perfect unless constructed with an equal weight each side of the center of the driving-wheel.

Second. By placing the said shaft in the above-mentioned position I am enabled to construct my machine in such a manner that all and every part of the gearing works in a direct line with the axle of the driving-wheel. This, it will be seen, is absolutely necessary in this arrangement, for were it placed in any other position it would be impossible to operate the sickle by means of the eccentric and sliding pinion-shaft without destroying the adjustability of the head-iron or the balance of the machine.

Third. By placing the line-shaft in said position I am enabled to use an anti-friction wheel of greater diameter than I could were said shaft placed in any other position. The advantages of a large anti-friction wheel are obvious, as all mechanics are acquainted with the fact that the greater the diameter of the wheel the less resistance is experienced from friction while the wheel is passing over even surface, and the greater the ease with which the wheel overcomes the resistance of bogs, mounds, stones, and all other impediments found on uneven surface.

Another advantage of placing the shaft at the highest point possible is to give the head-iron a greater scope of adjustability, for it will be seen that were the shaft placed at a lower point the head-iron could be raised only to a point to correspond thereto.

The object of extending the line-shaft entirely across the frame of the machine is to form an open unobstructed space between the driving-wheel and the anti-friction wheel, and also to admit of an anti-friction wheel being placed in the peculiar position herein shown and described. Said shaft is also provided with a bevel-wheel, C, which takes into a bevel-pinion, d , as clearly shown in Figs. 2 and 3. Said pinion is placed upon a shaft, E, which is provided with a crank, f , at its lower end. Said crank is provided with an anti-friction roller, g , Fig. 2, which works in a yoke, hk . (See Fig. 2.) Said yoke is provided with an adjustable back, as seen in Fig. 4, and is adjusted by means of set-screws yy . The object of the adjustable back is to enable the operator to adjust it in case the anti-friction roller or inner

side of the yoke becomes worn so as to work too loosely, and consequently produce a jarring unsteady motion of the sickle. Said yoke is attached to and forms a part of the sash I, which slides in suitable ways, *i i*, Fig. 5, and operates the sickle.

J is the sickle, which is attached to the sash by means of a pitman, *j*.

K is the finger-bar, which is attached to the head-iron, as seen in Figs. 1 and 4, and is composed of two separate pieces—one of wrought-iron and the other of cast-iron. The wrought bar is placed on the top of the cast bar and secured firmly to it. The object of this arrangement is to prevent the finger-bar from breaking or springing and setting, as it is liable to do, the former when made entirely of cast-iron and the latter when made entirely of wrought-iron.

L is the finger or sickle-guard, through which the sickle reciprocates, which is attached to the finger-bar, as seen in Figs. 1 and 4.

To the grain end of the finger-bar I attach a shoe or shield-piece, M, for the purpose of protecting the fingers and sustaining a portion of the pressure of the machine upon the ground.

N is the head-iron, which slides in suitable ways, *n n*, Fig. 1.

O is the anti-friction wheel, having its axle attached to an upright bar, P, which slides in suitable ways, *p p*, Fig. 1. The top of said bar is bent in the manner seen in Fig. 2, and presses against spring R, as seen in Fig. 2. *r r* are set-screws which take into the cross-beam S, and are used to set the spring at any desired height above it.

The advantages of the anti-friction wheel and the additional results produced by my device are as follows: My anti-friction wheel serves several purposes: First, by its adjustable feature I am enabled to allow any desired weight to bear on the head-iron; second, by its combination with the spring it assists the sickle-bar in accommodating itself to uneven surface; third, my machine is so constructed and the anti-friction wheel is placed in such a manner that the driving-wheel end of the machine from the bearings of the anti-friction wheel weighs about four times as much as the opposite end when the machine is in order for reaping. Therefore it will be seen that a sufficient amount of weight will rest on the driving-wheel to operate the sickle while reaping. By this arrangement I evade the necessity of placing a grain-wheel at the grain end of the finger-bar while reaping, thereby obviating in a great measure the side draft and allowing that portion of the machine to be made much lighter than it otherwise could be. The wheels in a working machine are five feet apart. The pole is placed at the center between them. When the machine is moved forward by the tongue the grain end of the machine will incline forward of the master-wheel end; but when it comes in contact

with the grain it will incline back to a right angle with the tongue. This advantage could not be obtained were the anti-friction wheel removed and one placed at the grain end of the sickle-bar, as in other reapers.

T is the reel, which receives its rotary motion from the line-shaft by means of the belt *t*.

U is a lever which is used for throwing the machine into and out of gear.

V is the pole.

W W, Fig. 3, are screws which are used for securing the head-iron to the frame of the machine.

w w w w are holes in the head-iron for the purpose of adjusting the machine to a high or low cut.

The object of the anti-friction wheel, when mowing, is to lessen the draft, obviate the side draft, and relieve the finger-bar from strain. This is all accomplished by merely forcing the screws *r r* down on the spring until the finger-bar bears the desired weight on the ground. This can be ascertained by raising the finger-piece with the hand. About twenty-five pounds is sufficient for cutting close an even surface; less or none at all on rough surface. This, however, every operator will decide for himself. If the shoe of the finger-bar raises on higher surface than the machine, the spring, being on a strain, helps to raise it. This prevents the finger-bar from springing. Consequently the sickle-bar or knife-bar reciprocate unobstructed. This obviates in a great measure the knife choking and clogging. When reaping I force the spring down. This, however, is to agree with the adjustable features of the head-iron for high or low cut.

The machine, as seen in the drawings, is adjusted for mowing. Now, to adjust the machine for reaping, take out the screws W W. This done, all that part of the machine shown in Figs. 4 and 5 (excepting the pinion only, which remains stationary and allows its shaft to slip through it) can be raised and secured at the desired height without affecting the gearing of the machine in the least. Thus we see that in my machine are embodied all the principles of a perfect mower and reaper. The perfect harmony in which this truly mechanical arrangement operates is enough to warrant its due appreciation by all who examine into its merits.

What I claim as my invention, and desire to secure by Letters Patent, is—

1. Placing the line-shaft directly above the vertical center of the spur-gear of the master-wheel, in the manner and for the purpose herein described.

2. The adjustable anti-friction wheel, in combination with the spring R and adjustable set-screws *r r*, in the manner and for the purpose herein described.

JARVIS CASE. [L. S.]
